[57] CLAIM

The ornamental design for a daybed, as shown and described.

DESCRIPTION

FIG. 1 is a front perspective view of a daybed showing my new design;

FIG. 2 is a side elevational view thereof, the opposite side elevational view being a mirror image;

FIG. 3 is a rear elevational view thereof;

FIG. 4 is a front perspective view of the daybed shown in FIG. 1 with the backrest cushions and the ruffled seat cover removed.

FIG. 5 is a side elevational view thereof, the opposite side elevational view being a mirror image; and,

FIG. 6 is a rear elevational view thereof.

FIG. 1

FIG. 4
